May 8, 1951

10 Claims. (Cl. 118—410)

1

This invention relates to back-seam-strengthening machines of the type in which a thermoplastic material is extruded upon the seam.

The reinforcement or strengthening of back seams has been commonly carried out by the application of a reinforcing tape secured to the back seam by adhesive. Such machines, in view of the curved characteristic of the upper at the back seam, are necessarily complicated and expensive. It has, however, been suggested in Letters Patent of the United States No. 2,325,656, granted August 3, 1943 on the application of John J. Brophy, that the back seam may be strengthened by coating the inturned edges of the upper with an adhesive material such as a thermoplastic resin which will harden and become nontacky, flexible and tough.

Accordingly, an object of the invention is to provide an improved machine for applying a coating material to the projecting back-seam ribs of shoe uppers which shall be quicker to operate and which will give more effective results.

It is well understood that closed uppers are more readily handled if they can be kept in a right-side-out condition although it is evident that this requires the application of the coating material to the projecting seam parts which lie upon the inside of the upper. One feature of the invention resides in an improved arrangement, facilitating this manner of handling, which in its illustrated form comprises a work-supporting post having an extruding outlet at its upper end so that the seams may be guided over the post in right-side-out condition as the material is applied thereto.

Other features of the invention lie in the provision of suitable guides or dams to prevent overflow of the material issuing from the outlet and in the utilization of a heated spreader, the temperature of which is very much higher than that of the post, for effecting a deeper penetration of the material and for removing any surplus from the inner surface of the upper. The illustrated machine also embodies a control valve by means of which the operator may regulate the out-flow of cement from the opening at the top of the supporting post and a feed roll positioned for engagement with the outside of the upper just above that post.

These and other features of the invention will best be understood from a consideration of the following specification taken in connection with the accompanying drawings in which

Fig. 1 is a side elevation of the complete machine;

Fig. 2 is a vertical section through the work supporting post;

2

Fig. 3 is a plan view of the top of this post on an enlarged scale; and

Fig. 4 shows an enlarged view from the front of the machine illustrating the contours of the work, a feed roll, a crease guide and the work supporting post.

The illustrative machine comprises a base 10 carried at the top of a supporting column 12, this base being combined with a box-like frame 14 in which there is supported a receptacle 16 having a supply of coating material which is introduced therein by removing a cover 18. Inside this receptacle the material is melted by heat from an electric unit 20 which, for one illustrative material, heats it to about 270° F. The material is removed from this receptacle by means of a gear pump 22 connected by a conduit 24 to passages within a work supporting post 26. This post has at its upper end a seam receiving groove 28 in which there is an outlet opening 30 (Fig. 3).

The pump is driven by means of a chain 32 connecting it to a drive shaft 34 on which there is a pulley 36 connected by a belt 38 to a source of power such as an electric motor (not shown). The pressure at the delivery outlet of the pump is controlled by means of a by-pass 40 having in it a spring-pressed valve the action of which may be regulated by turning a screw 42. It will be seen that the conduit 24 is contained within a box-like structure 44 providing an oil bath kept at a temperature of about 315° F. by means of heating units 46. The front end of the chamber is closed by a plate 48 in which the conduit 24 is sealed and to which the post 26 is attached by means of bolts 50.

The post 26 (Fig. 2) has a large bore 52 in which there is positioned a valve rod 54 having a shouldered tip 56 adapted to enter and close the outlet 30. This rod which is normally held up in closed position by means of a spring 58 is guided in a threaded bushing 60 against which one end of the spring rests. The upper end of the spring presses against a gland packing 62 which is associated with the underside of an enlarged portion 64 of the rod so that the adhesive material cannot escape into the portion of the bore containing the spring. The upper end of the valve rod is fluted at 66 and slides in a reduced bore 68 which has at its upper end a shoulder 70 cooperating with a shoulder at the top of the valve rod.

The post also has a supplemental passage 72 to which the melted material is admitted through an opening 74 positioned in alignment with the end of the conduit 24. The upper end of this

supplemental bore is joined by a short transverse passage 16 with the enlarged bore 52 so that when the valve rod 54 is depressed to take its tip 56 out of the outlet opening 30 the material will flow through the flutes 66 into that opening. It will be noted that the groove 28 at the top of the post is enlarged at 18 (Fig. 3) adjacent to the outlet opening 30 to permit the extruded material to go up the sides of the seam-forming rib 30 of a shoe upper 82 (Fig. 4).

The outer end of the rib-receiving groove 28 is dammed by a depressible gate 84 having a groove 85 shallower than the groove 28 and which is mounted for sliding movement on the front of the post by means of a holding plate 86 in back of which there is a spring 88. The up and down movement of this gate is restricted by means of a pin 90 passing through a slot 92 in the plate. It will be noted that the upper end of the gate is rounded as shown in Fig. 4, it being depressible by the pressure of a shoe upper passed thereover.

After the rib formed by the seam parts 30 has passed over the top of the post 26 it is received in a groove 94 extending along the top of a spreader block 96. This block, which is supported by a bracket 98 attached to the cover of the oil chamber 44, is provided with an electric heater 100 by which its temperature may be raised to some 330° F. This temperature may be regulated by suitable control devices (not shown) and it will be noted that the spreader block is connected to the post 26 by only a very shallow neck 102 to the end that there shall be a minimum loss of heat by conduction from the spreader block to the post 26. The block is also separated from its supporting bracket by a sheet 104 of insulating material. The higher temperature of the spreader block 96 causes the plastic to be momentarily more fluid and enables the plastic to be forced into the stitches of the seam as the work is pressed down against the block. Since the groove 94 is shallower than the groove 28, spreader block 96 acts also as a scraper to remove surplus material and as a dam to prevent accidental escape of the material at the inner end of the groove 28. One suitable and convenient thermoplastic material for this purpose is, for example, a mixture of high molecular weight polyvinyl acetate, wood rosin and plasticizer. It will be understood that the above-mentioned temperatures are suitable for this particular material but that other materials may be used, for which a different set of temperature values will be more suitable.

Above the post 26 there is rotatably supported a rubber feed roll 110 having a contour (Fig. 4) similar to that of the upper end of the post and the gate 84, this roll being driven in the direction of the arrow in Fig. 1 so that when it is pressed against the work the latter will be carried along the groove 28 over the outlet opening 30 and through the groove 94 of the spreader block. This feed roll 110 is journaled in plates 112 (Fig. 1) carried at the end of a lever 114 pivoted upon a rod 116 carried in a bracket 118 attached to the top of the frame 14. Attached to and journaled in the outer end of this lever 114 is a pulley 120 having a drive connection to the feed roll through a series of pinions 122, 124, and 126. The pulley is driven from the main shaft 34 by means of a crossed belt leading to a smaller pulley 128 on the rod 116 and this pulley 128 is driven by means of a chain 130 from the main shaft 34. Inasmuch as the pulley 128 is coaxial with the pivot rod 116, the drive is unaffected by the tilting of the lever 114.

The tilting movements of lever 114 may be effected by means of a rod 132 joined to a lever 134 mounted near the base of the frame on a rod 136 supported in brackets 138 attached to the frame. The forward end of this lever 134 has a reduced portion 140 adapted to be brought into engagement with an adjustable abutment 142 threaded to and locked upon a depending portion of the valve rod 54. The lever 134 is joined to a treadle (not shown) by a rod 144. It will also be noted that the upper end of the connecting rod 132 slides through the lever 114 but is surrounded by a spring 146 resting against a collar 148 and held under pressure by a stop nut 150. Thus when the treadle is depressed the feed roll 110 is brought yielding into engagement with the outside of an upper 82 (Fig. 4) and the valve rod 54 is depressed to open the outlet 30 at the top of the post. A seam-crease guide 152 is carried by plates 112 at the forward end of the lever 114 and this guide is tapered at 154 (Fig. 4) so as better to fit in the crease of the upper.

When the coating material has been fully heated and is ready for delivery to the outlet opening 30, an upper 82 in right-side-out condition may be placed upon the post 26 depressing the gate 84 and entering the guiding groove 85 therein. As the operator depresses the treadle connected to the rod 144 the valve rod 54 will be depressed and coating material extruded through the outlet opening. The work will be moved forward by the feed roll 110 and the seam rib 30 will pass along the shallower groove 94 of the spreader 96 which serves both as a dam at the rear end of the groove 28 and as a scraper to remove surplus material from the seam rib. In passing over the spreader block 96 the temperature of the material is momentarily raised to a substantial extent and thus the material is made more fluid so that it penetrates the stitches of the seam and sometimes the leather thereof. The spreader block serves also to iron the material into the seam and contacts the sides thereof. As the result of the characteristics of the material employed it quickly hardens after the work is removed from the machine and effects a strengthening and reinforcing of the back seam.

Having thus described our invention, what we claim as new and desire to secure by Letters Patent of the United States is:

1. In a machine for coating the back-seam rib of a shoe upper, a support having an outlet opening and upon which an upper may be positioned in right-side-out relation, rib-guiding means to align the rib with said opening, driven means for moving said upper over said support in the direction of the heel seam, means for extruding a coating material through said opening, and spreader means over which the work passes for reducing the viscosity of the extruded material beyond the point of application so that it will penetrate the seam.

2. In a machine for coating the back-seam rib of a shoe upper with a thermoactive adhesive material, a support narrower than an upper having an outlet opening narrower than said rib and upon which an upper may be positioned in right-side-out relation with the edge of a rib closing said opening, driven means resting on said upper over said support to move it in the direction of the heel seam, means for heating the thermoactive adhesive material, means for extruding said material through said opening, and heated means engaging the coated rib for reducing the viscosity of the material which has been ex-

truded upon the work thereby the more effectively to spread the material thereon.

3. In a machine for coating the back seam of a shoe upper, a work support provided with an outlet opening upon which a back seam may be supported in right-side-out relation, movably mounted means for supporting a feed roll for engagement with the outside of the upper adjacent to the back seam, a seam crease guide on said movably mounted roll support, extruding means supplying coating material to said outlet, an outlet valve, and operator-controlled means for moving the feed roll into engagement with the upper and opening said outlet valve.

4. In a machine for coating the projecting back seam of a shoe upper, a post the upper portion of which is provided with a transverse seam-receiving groove intersecting the front and rear faces of said post, means for extruding a coating material into said groove for application to the seam, and devices having shallower grooves positioned at either end of said groove for preventing undue spread of the coating material.

5. In a machine for coating the projecting back seams of shoe uppers, a supporting post having a front-to-back seam-receiving groove at its upper end, a passage opening into said groove through which coating material may be extruded onto the seam, and a depressible gate slidably mounted on the machine for up-and-down movement at the front of the groove, said gate being resiliently supported whereby it may be moved out of the way by the pressure of the work while acting to dam one end of the groove when no work is being presented.

6. In a machine for coating the projecting back-seam ribs of shoe uppers, a supporting post having a front-to-back seam-receiving and guiding groove at its upper end, and having a passage opening into said groove through which coating material may be extruded onto the seam, said groove being widened only in the neighborhood of said opening to allow a coating of the

sides of the seam rib, and a feed roll for moving an upper over said post.

7. In a machine for coating the back-seam ribs of shoe uppers, a work-supporting post having at its upper end a transversely extending rib-fitting groove, means for extruding thermoactive material into said groove to coat the seam of an upper in a right-side-out position thereon, a treadle-operated valve controlling said extruding means, a receptacle for a supply of material, means for heating the coating material in the receptacle, a spreader arranged adjacent to the far end of the rib-receiving groove, means for moving the work toward said spreader, and means for maintaining the temperature of such spreader substantially higher than the temperature imparted to the post by the cement.

8. A machine as in claim 7 in which a major portion of the spreader body is spaced from the post.

9. In a machine for coating the back seams of shoe uppers, a post for supporting the rear end of a shoe upper in right-side-out condition, said post having a seam-receiving groove provided with an outlet opening, means for supplying thermoactive material to said outlet opening, a grooved gate positioned at the work-entering end of the groove with the bottom of its groove higher than the bottom of the groove in the post, a grooved spreader positioned at the leaving end of the groove, and means for moving the work in the direction of the grooves from post to spreader.

10. A machine as in claim 9 in which the grooved gate at the entering end is movably mounted on the post so that it is depressible by the work.
